CLAIM

The ornamental design for a dental air/water syringe tip, as shown and described.

DESCRIPTION

FIG. 1 is a front, right perspective view of a dental air/water syringe tip showing a first embodiment;

FIG. 2 is a rear, right perspective view thereof;

FIG. 3 is another rear, right perspective view thereof;

FIG. 4 is a right-side elevation view thereof;

FIG. 5 is a left-side elevation view thereof;

FIG. 6 is a front elevation view thereof;

FIG. 7 is a rear elevation view thereof;

FIG. 8 is a top plan view thereof;

FIG. 9 is a bottom plan view thereof;

FIG. 10 is a front, right perspective view of a dental air/water syringe tip showing a second embodiment;

FIG. 11 is a rear, right perspective view thereof;

FIG. 12 is another rear, right perspective view thereof;

FIG. 13 is a right-side elevation view thereof;

FIG. 14 is a left-side elevation view thereof;

FIG. 15 is a front elevation view thereof;

FIG. 16 is a rear elevation view thereof;

FIG. 17 is a top plan view thereof; and,

FIG. 18 is a bottom plan view thereof.

All features in phantom line are for the purpose of illustrating environmental structure and form no part of the claimed subject matter. Color and texture may or may not form part of the claimed design or designs without departing from the design disclosed.

1 Claim, 12 Drawing Sheets

Related U.S. Application Data

a division of application No. 29/564,356, filed on May 12, 2016, now Pat. No. Des. 832,443.
